Demian K. Jackson(57) **CLAIM**

The ornamental design for a bottle cage connection seat, as shown and described.

DESCRIPTION

FIG. 1 a perspective view of a bottle cage connection seat showing my new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

Those portions of the illustrated design illustrated by broken lines form no part of the claimed design.
